C. H. SHAW.
PHONOGRAPH SOUND BOX.
APPLICATION FILED OCT. 29, 1919.

Patented July 20, 1920.

By his Attorneys
Kerr, Page, Cooper & Hayward

UNITED STATES PATENT OFFICE.

CHARLES H. SHAW, OF BABYLON, NEW YORK.

PHONOGRAPH SOUND-BOX.

1,347,059.

Specification of Letters Patent. Patented July 20, 1920.

Application filed October 29, 1919. Serial No. 334,105.

To all whom it may concern:

Be it known that I, CHARLES H. SHAW, a citizen of the United States of America, residing at Babylon, in the county of Suffolk 5 and State of New York, have invented certain new and useful Improvements in Phonograph Sound-Boxes, of which the following is a full, clear, and exact description.

As is well known, phonographic records 10 are of two general classes,—one known as "hill-and-dale," in which the undulations of the sound record are perpendicular to the surface, and the other known as "laterally cut," in which the undulations are parallel 15 to the surface, or transverse to the groove. As a result, reproducers (or "sound-boxes," as they are frequently called) designed for one type of record are not inherently adapted for use with the other type, and accordingly 20 numerous attempts have been made to provide a sound-box which by suitable adjustment can be used with both types. So far as I am aware, the prior devices for the purpose have all involved shifting or turning 25 the sound-box itself, or shifting the needle to a different holder, or using a special type of needle. Such expedients are inconvenient, however, and in consequence 30 none of them has come into very extensive use. I have therefore been led to devise my present invention, which has for its chief object to provide a sound-box or reproducer which will play either type of record without change or adjustment of any kind whatsoever. 35

In carrying out my invention in the preferred manner I provide a diaphragm and diaphragm chamber, as usual, and on the edge of the latter I mount two spring sound- 40 arms, preferably at right angles to each other, extending into engagement with the diaphragm at the center of the latter, and diametrically opposite to these I provide two shorter spring arms which do not engage 45 the diaphragm. Below these four arms I mount on the chamber a rigid member or carrier, in which the needle-holder is spring-supported. The needle-holder is suitably connected to the four spring arms, 50 so that it is supported partly by the latter and partly by the rigid carrier. In use the device is arranged with the diaphragm downward and slightly inclined, and with one sound-arm radial to the disk-record or 55 parallel to the axis of a cylindrical record. The other sound-arm is therefore in a ver-

tical plane which is practically tangent to the record groove. Then with a lateral record the first sound-arm actuates the diaphragm, whereas with a hill-and-dale record 60 the second or tangent arm actuates the diaphragm.

The embodiment above outlined is illustrated in the accompanying drawing, in which—

Figure 1 is a side view of the sound-box, attached to the tone arm of a phonograph or talking machine, and arranged in position for playing. In dotted lines the sound-box is shown turned up to a convenient position 70 for changing the needle.

Fig. 2 is a cross section of the sound-box on a larger scale, taken on a plane indicated substantially by the line 2 of Fig. 3.

Fig. 3 is a bottom plan view of the sound 75 box.

Fig. 4 is a fragmentary horizontal section on line 4—4 of Fig. 2.

Fig. 5 is a fragmentary bottom plan view of the central portion of the diaphragm, 80 illustrating the button with which the sound-arms engage.

Fig. 6 is a detail sectional view.

The diaphragm chamber has a heavy rim or wall 10 provided with a flange 11 by 85 which the rubber rings 12 and the interposed diaphragm 13 are held in position. The back of the chamber is provided with a curved neck 14, which is removably and rotatably fitted to the swinging tone arm 15. 90

On the center of the diaphragm is a button 16, having in its face a cruciform groove, that is, two grooves, 17, 18, Fig. 5, crossing at right angles, and fixedly connected to the rim 10 by their outer ends 95 are two spring sound-arms 19, 20, extending radially inward at right angles to each other and preferably about parallel to the diaphragm. The pointed inner ends of the sound-arms are bent upwardly and bear in 100 the grooves 17, 18, respectively, of the button 16, as clearly indicated in Fig. 2. Diametrically opposite to the sound-arms are two spring carrier-arms 21, 22, fixedly connected by their outer ends to the rim 10 105 and extending radially inward at right angles to each other but terminating considerably short of the center of the diaphragm. The four spring arms may be connected to the rim by means of lugs 23 and are in 110 the same plane.

Below the arms 19, 20, 21, 22 is a spider-

shaped carrier 24 having four radial legs 25 firmly fixed at their ends to the rim 10 in any convenient manner, as by means of lugs 26, at points between the aforesaid 5 arms. At the center of the carrier is a button 27 having a downwardly open recess 28.

Below the carrier 24 is an axial needle-holder 29 having at its top or inner end 10 four radial fingers 31, 32, 33, 34, immediately under the four spring arms 19, 20, 21, 22, respectively. The holder 29 has at its lower end the usual needle-socket and clamping screw 35 for the needle 36, and 15 at its upper end the needle-holder has a pointed lug 37 bearing in the recess 28, Figs. 2 and 6. The four fingers have threaded through them at their outer ends four screws 38, the rounded upper ends of 20 which bear in shallow recesses in the undersides of the four spring-arms. Lock-nuts are provided to lock these screws in adjusted position.

Below the needle-holder fingers 31, 32, 25 33, 34, and encircling but out of contact with the downwardly extending portion of the needle-holder is a centrally apertured disk-shaped carrier 40 firmly mounted on the four members 25, as by means of lugs 30 41, and between the disk and the needle-holder fingers is a dished or downwardly concave centrally apertured spring 42. The latter at its center bears against the fingers of the needle-holder, and has four 35 radial extensions or fingers bearing on the disk or carrier 40 near the edge thereof. It will therefore be seen that the needle holder floats, as it were, on the carrier 40 and that its four fingers 31, 32, 33, 34 are held 40 (through the medium of the screws 38) in connection with the four spring arms 19, 20, 21, 22.

Assume now that the sound-box is in the 45 position shown in solid lines in Fig. 1, and that the needle is in the hill-and-dale groove of a disk record. As the groove passes under the needle the undulations of the groove vibrate the needle and needle-holder in the general direction of the small arrows in 50 Fig. 1. In this vibratory movement the needle holder operates like a bell-crank lever fulcrumed on the lug 37 and the two screws 38 which lie in the plane transverse to the record groove, while the finger 33, 55 Figs. 1 and 2, flexes the spring-arm 21 idly. At the same time the finger 31 flexes the sound-arm 19 and thereby vibrates the diaphragm. If a laterally cut record is in use, the needle-holder vibrates in a plane perpendicular to the plane of the drawing, on 60 arms 19, 21, and stud 27 as bearings, while finger 32 actuates sound-arm 20 (thereby vibrating the diaphragm) and flexes arm 22 idly. It will thus be seen that the playing 65 or operative position of the sound-box

is invariable, that the sound-box is not shifted or altered in position, nor does it have to be adjusted or the needle, needle-holder or any other part shifted to play different types of records; though of course 70 a needle or stylus of appropriate shape will be used with records requiring a ball- or round-pointed needle. It will also be seen that the needle can rock or vibrate in either of two planes which are perpendicular to 75 the diaphragm and that in each case the vibrations of the needle-holder are transmitted to the diaphragm in such manner as to act on the latter in a direction perpendicular thereto. Or, stated otherwise, 80 the needle-holder can vibrate in the plane of, and thereby actuate, either sound-arm, and when vibrating transversely to the plane of one of the arms it actuates the other arm, and vice versa. 85

It is to be understood that the invention is not limited to the specific construction herein illustrated and described but can be embodied in other forms without departure from its spirit. 90

I claim.

1. A sound-box for phonographs, comprising a diaphragm chamber, a diaphragm, a needle-holder, means carried by the diaphragm chamber and supporting the needle-holder co-axially with the diaphragm, and connecting means between the diaphragm and the needle-holder enabling the latter to vibrate laterally or vertically and thereby play a laterally cut or a hill-and-dale record 100 without shifting or adjustment of the sound-box or any of its parts. 95

2. A phonographic sound-box having an invariable playing position and provided with a diaphragm, a needle-holder co-axially with the diaphragm, and connecting devices 105 between the diaphragm and the needle-holder enabling the latter to vibrate vertically or laterally.

3. In a phonographic sound-box, a diaphragm, a pair of vibratory sound-arms connected to the diaphragm at the center thereof and extending radially at an angle to each other, and a needle-holder common to both arms and connected therewith to 115 actuate one or the other according to the type of record with which the sound-box is used.

4. In a phonographic sound-box, a diaphragm, a pair of vibratory sound-arms 120 connected to the center of the diaphragm and extending radially at an angle to each other, supporting means for the outer ends of the sound-arms, a needle-holder perpendicular to the diaphragm and mounted to vibrate transversely of either sound-arm, and means connecting the needle-holder to the sound-arms and enabling the needle-holder when vibrating transversely of either arm 125 to vibrate the other arm. 130

5. In a phonographic sound-box, a diaphragm, a pair of vibratory sound-arms connected to the center of the diaphragm and extending radially at an angle to each other, and a needle-holder mounted to vibrate transversely of either sound-arm and having diverging fingers connected to the respective sound-arms. 25
6. In a phonographic sound-box, a diaphragm, a pair of vibratory sound-arms connected to the diaphragm at the center thereof and extending radially at an angle to each other, a pair of supporting arms extending radially inward opposite to the sound-arms, and a needle-holder having radial fingers connected to the respective sound-arms and supporting arms. 30
7. In a phonographic sound-box, a diaphragm, a pair of sound-arms connected to the diaphragm at its center and extending radially at an angle to each other in a plane below the diaphragm, a pair of supporting 35
